(57) **CLAIM**

The ornamental design for a watch dial, as shown and described.

DESCRIPTION

FIG. 1 is an enlarged perspective view of a watch dial showing my new design;

FIG. 2 is a front elevational view thereof;

FIG. 3 is a right side elevational view thereof; the left side elevational view is a mirror image of the right side elevational view;

FIG. 4 is a rear elevational view thereof; and,

FIG. 5 is a top plan view thereof; the bottom plan view is a mirror image of the top plan view.

The broken lines shown in FIGS. 1, 2, 3, and 5 show portions of the watch dial that form no part of the claimed design.

1 Claim, 3 Drawing Sheets(56)
